(57) **CLAIM**

The ornamental design for a wall-mounted tire pressure monitoring sensor, as shown and described.

DESCRIPTION

FIG. 1 is an overhead perspective view of an embodiment of a wall-mounted tire pressure monitoring sensor showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The portions depicted in broken lines are shown for the purpose of illustrating portions of the wall-mounted tire pressure monitoring sensor and form no part of the claimed design.
